UNITED STATES PATENT OFFICE.

JOHN W. FRASER AND JOHN D. WILSON, OF LONDON, CANADA.

VACUUM-PUMP.

SPECIFICATION forming part of Letters Patent No. 496,559, dated May 2, 1893.

Application filed June 27, 1892. Serial No. 438,241. (No model.) Patented in Canada June 22, 1892, No. 39,177.

To all whom it may concern:

Be it known that we, JOHN W. FRASER and JOHN D. WILSON, subjects of the Queen of Great Britain, residing in the city of London, 5 in the Province of Ontario, Canada, have invented certain new and useful Improvements in Pumps, (for which we have obtained a patent in the Dominion of Canada, No. 39,177, granted June 22, 1892,) of which the following 10 is a full, clear, and exact description, reference being had to the accompanying drawings, which form a part of this specification.

Our invention relates to improvements in pumps which employ an elastic tubing and 15 suitable means for compressing the same whereby a vacuum is formed in the tubing which is quickly filled by the fluid which is being raised by the pump, and our invention consists of certain features of novelty which 20 will be hereinafter fully described and specifically pointed out in the claims.

In the accompanying drawings: Figure 1 is a side view of our improved pump, and Fig. 2 is an end view thereof, the supporting 25 bracket and elastic tube being shown in section.

Referring to the drawings:—A represents the base portion of the curved supporting bracket A', B the elastic tube supported on 30 said curved bracket, and D flanges or guides formed integral with the bracket to prevent the accidental displacement of the elastic tube. The base portion of the bracket is provided with flanges c which guide the standards E, 35 when the latter are being adjusted.

The standards E are adjusted vertically by means of slots e formed in their lower ends and the pin F which also secures them to the base portion A. In the upper ends of said 40 standards sockets d are formed for the reception of the trunnions of the piston G' which consists of the hub G and the radially extending arms I. The latter are forked at their outer ends and have mounted therein 45 the rollers J, which bear upon the elastic tubing B. Rotary motion is imparted to the piston G' by means of the crank-handle H, which is keyed to the trunnions of the said piston.

In order to obtain the best results from this device the radial arms of the piston should 50 be so arranged that one of the rollers in the arms will be in engagement with the elastic tube while the preceding one is being disengaged.

R. represents a screw clamp secured to the 55 base A for attaching the pump to a support in any position as the circumstances may require.

The operation of our pump is as follows:—One end of the tube is placed in the liquid 60 to be raised, and the piston rotated by the crank H, so that the rollers will move along the tube from said end. During the rotation of the piston the rubber tube is compressed by the rollers as shown in Fig. 2, and as they 65 move along the tube a vacuum is formed behind them into which the fluid is forced by the pressure of the atmosphere, and is ejected from the other end. It will readily be seen that the pressure upon the tube can be regulated by the raising or lowering of the standard, and when the pump is not in use the 70 piston can be raised from the said tube and thus relieve the pressure and thereby retain its elasticity and wearing qualities. 75

This invention has been described in connection with liquids or fluids, but air or gases could be acted on in the same manner.

Having thus described our invention, what we claim as new, and desire to secure by Letters Patent, is—

1. In a pump, the combination of the base, the curved supporting bracket formed integral with the base and having the flanges or guides c formed on it, the pair of standards 85 provided at their lower ends with slots, and at their upper ends with eyes and adjustably secured between the guides c, on opposite sides of the bracket, by a pin passing through the base and said slots, and the piston carrier secured between the upper ends of the standards by means of the axis passing through said parts, substantially as shown and described.

2. A pump consisting of a suitable base, a 95 curved bracket supported on the base and

having guides *c*, the pair of vertical standards adjustably secured between the guides *c*, on opposite sides of the curved bracket by means of slot and pin connection, and the rotary piston having a fixed bearing in the upper ends of said standards, substantially as and for the purpose set forth.

5 In testimony whereof we affix our signatures

in the presence of the two undersigned witnesses.

JOHN W. FRASER.
JOHN D. WILSON.
